UNITED STATES PATENT OFFICE

GEORGE VAN DE RIET, OF HOLLAND, MICHIGAN, ASSIGNOR TO WEST MICHIGAN FURNITURE COMPANY, OF HOLLAND, MICHIGAN, A CORPORATION OF MICHIGAN

DESIGN FOR A DRESSING TABLE

Application filed August 22, 1932. Serial No. 44,661. Term of patent 3½ years.

To all whom it may concern:

Be it known that I, GEORGE VAN DE RIET, a citizen of the United States, residing at the city of Holland, in the county of Ottawa and State of Michigan, have invented a new, original, and ornamental Design for a Dressing Table, of which the following is a specification, reference being had to the accompanying drawing, forming a part thereof.

The figure is a perspective view of a dressing table showing my new design.

I claim:

The ornamental design for a dressing table, as shown.

GEORGE VAN DE RIET.
